(57) **CLAIM**

The ornamental design for a table, as shown and described.

DESCRIPTION

FIG. 1 is a top plan view of a table, showing my new design;
FIG. 2 is a perspective view thereof;
FIG. 3 is a perspective view showing the table in exploded condition;
FIG. 4 is a rear elevational view thereof;
FIG. 5 is a left side perspective view thereof;
FIG. 6 is a front elevational view thereof;
FIG. 7 is a right side perspective view thereof;
FIG. 8 is a bottom perspective view thereof; and,
FIG. 9 is a second bottom perspective view thereof.
The broken lines showing the drainage holes are for the purpose of illustrating environmental structure and form no part of the claimed design.
